UNITED STATES PATENT OFFICE.

JAMES VRAYLAS, OF PEORIA, ILLINOIS.

DESIGN FOR A WALL CUSIPDOR.

Application filed June 30, 1923. Serial No. 6,633. Term of patent 3½ years.

To all whom it may concern:

Be it known that I, JAMES VRAYLAS, a citizen of the United States, residing at Peoria, in the county of Peoria and State of Illinois, have invented new, original and ornamental Design for Wall Cuspidor, of which the following is a specification, reference being had to the accompanying drawing, forming part hereof.

I claim:

The ornamental design for a wall cuspidor, as shown.

In testimony whereof I affix my signature in presence of two witnesses.

JAMES VRAYLAS.

Witnesses:

HAZEL G. BROWN,
L. M. THURLOW.
